UNITED STATES PATENT OFFICE.

HOWARD A. LADUE, OF DETROIT, MICHIGAN.

COIN-CONTROLLED VENDING-MACHINE.

937,820.

Specification of Letters Patent. Patented Oct. 26, 1909.

Application filed October 31, 1907. Serial No. 399,987.

To all whom it may concern:

Be it known that I, HOWARD A. LADUE, a citizen of the United States, residing at Detroit, in the county of Wayne and State 5 of Michigan, have invented certain new and useful Improvements in a Coin-Controlled Vending-Machine, of which the following is a specification.

My invention has for its object to provide 10 an improved coin-controlled or slot machine, the same being more especially designed for handling plug tobacco and analogous packages, the same being adapted for handling various articles of merchandise.

15 My invention consists of the construction, combination and arrangement of devices and appliances hereinafter described and claimed and illustrated in the accompanying drawings, in which,

20 Figure 1 is a view in perspective. Fig. 2 is a view in section on the line 2—2, Fig. 3. Fig. 3 is a section on the line 3—3, Fig. 1, showing the mechanism in operative position. Fig. 4 is a view similar to Fig. 3, with 25 a portion of the case in elevation, showing features of the mechanism in operative position. Fig. 5 is a view in perspective of one of the feeding carriages or plungers. Fig. 6 is a fragmentary view showing the mechanism 30 for intermittently rotating the shaft carried by the swinging frame. Fig. 7 is a view in section on the line 7—7, Fig. 2. Fig. 8 is an enlarged section through the coin-controlled mechanism. Fig. 9 is a plan view of mechanism illustrated in Fig. 8. Fig. 10 is a view in section on the line 10—10, 35 Fig. 9. Fig. 11 is an enlarged fragmentary view of the discharging or feeding device shown in the act of delivering one of packages, at the same time supporting the column 40 of packages. Fig. 12 is a view in section on the line 12—12, Fig. 11. Fig. 13 is a view in perspective of the filler plate. Fig. 14 shows the plate applied to the column of 45 packages. Fig. 15 is a view in section on the line 15—15, Fig. 3, looking upward. Fig. 16 is an enlarged view at the upper corner of one of the magazines showing the method of putting certain features of the 50 mechanism together.

I have found that packages corresponding in size to that of plug tobacco, cigarette boxes, etc., cannot be operated by the same

principle used in the handling of smaller packages, such as gum or other articles. 55 Present machines of an analogous nature force the lowest package of a magazine into its chute or proper receptacle by means of bars, rods, plates, jaws, etc., moving in one plane and returning in the same; relying upon gravity to make the next package fall 60 into the position vacated, each package above being called upon to drop in a restricted vertical path a distance equal to the thickness of the package. When a package of the bulk and thickness of plug tobacco is used the lowest package can be thrust from those above without difficulty, but the second package when allowed to take 65 its own course will fall with the free end foremost, while the other end is being held up by the thrusting mechanism. It will thus take an inclined position in the magazine, due to the fact that the diagonal of a rectangular package is longer than the base, 70 and therefore occupies the necessary clearance in the magazine. The packages above the inclined one necessarily fall in a similar position, and the result is a balled up condition in the magazine. If the dimension, in 75 question, of a magazine was made equal to the diagonal of the package, plus necessary clearance, the same balled up state of affairs would take place in the magazine, due to 80 too much freedom of lateral movement of 85 the packages. Consequently, packages of this size must be kept in a horizontal position while being lowered vertically.

One purpose of my invention is to remedy 90 the difficulties above mentioned.

For the reasons stated, it is not known that any other machine of this class has heretofore been adapted for handling plug tobacco, especially.

I carry out my invention as follows: In 95 the drawings the numeral 1 denotes any suitable inclosing case, provided with a removable cover 2, with a coin run-way 3, a series of boxes or magazines containing the articles of merchandise located within the case, 100 preferably multiple in number.

Certain features of my invention are adapted for operation with only a single box or mechanism, four, however, being shown in the accompanying drawings, the same being indicated by the numeral 4. The front 105

of the case is provided preferably, with transparent openings 5, through which may be seen an internal revenue stamp upon the articles of merchandise, if required. The 5 case 1 is also provided with a separable inclosing and supporting base 6. A swinging frame 7 is also supported within the case, said frame being preferably provided with upwardly extending arms 8 jointedly engaged at their upper ends with the case, as indicated at 9. The swinging frame carries an intermittently rotatable shaft 10. Supported within the base of the machine are a series of guide frames or tracks 11, equal in 10 number to the number of magazines, the guide frames being located beneath the lower extremities of the respective magazines. In these guide frames or tracks are supported corresponding reciprocating feeding plungers or carriages indicated at 12, their reciprocation being caused by the movement 15 of the swinging frame.

The swinging frame is actuated by mechanism controlled by a coin deposited in the 20 run-way as follows: At the base of the run-way are located two companion reciprocating coin catchers, the one located toward the rear shown at 13, sliding upon suitable guides supported in the base of the case. 25 The other coin catcher 15 is located in front of the rear catcher, and is supported in the base of the case, the front coin catcher telescoping within the rear catcher, as indicated in the drawings. Said catchers are 30 respectively provided with elongated open slots 16 and 17, the two slots combined being of sufficient size to receive and hold a coin deposited therein from the run-way, when in normal position. The rear catcher 35 is provided with a rack 18 and the front catcher with a shoulder or dog 19. Supported adjacent to the catchers is a spring 20 provided with a tooth 21 to engage the rack, and with an additional tooth 22 to engage 40 the dog 19. The dog 19 and tooth 22 have adjacent beveled faces, as shown. The two catchers are supported in any suitable manner, as upon brackets 23 and 24, the rear catcher being also mounted upon upper 45 guide rods 25 and lower guide rods 26. One of the guide rods is preferably adjustable, having a threaded engagement at its rear end in the adjacent bracket 24, as shown at 50 27, the adjustable guide rod being provided 55 with a shoulder 28 to engage against the forward end of the rear catcher indicated at 29, and is shown also provided with a head 30 for conveniently adjusting the same to regulate the length of the slots 16 and 17. 60 The forward catcher may be constructed in any suitable manner, the same being provided with a push rod 31 extending to the exterior of the base and provided with an internal retracting spring 32. A retaining

nut 33 has a threaded engagement through 65 the base and with an arm 34. The lower side of the push rod is constructed with an elongated slot 35 to permit of its reciprocation, and also to prevent same from turning. The inner end of the push rod has a threaded 70 engagement with the forward catcher, as shown at 36. A stop rod 37 is threaded at its inner end into the push rod, as indicated at 38. The movement of the forward catcher, it will be evident, may be regulated 75 by the threaded engagement of the rod 37 therewith, already noted. The outward movement of the push rod may be limited by the rod 37 striking against the arm 34. It will readily be seen that when a coin has 80 fallen from the run-way into the slots of the catchers, that force applied to the push rod will move both catchers rearward, disengaging the dog 19 from the tooth 22 of the spring 20, in consequence of which the 85 tooth 21 of the spring will ride upon the rack 18 as the rear catcher recedes or is moved rearward. When the limit of movement of the push rod is reached, the tooth 21 engaging the rack will hold the rear 90 catcher from returning to normal position until said tooth is disengaged from the rack. Meanwhile, the forward catcher receding to normal position will release the coin from the slots of the catchers and permit the coin 95 to drop into a coin receptacle or money drawer 39 beneath the catchers, said drawer located in a suitable case 14. As the forward catcher recedes toward its normal position by the action of the retracting spring 100 32, the dog 19 coming into contact with the tooth 22 of the spring, will force the spring back, disengaging its tooth 21 from the rack, permitting the rear catcher to move forward 105 into normal position, until it strikes the shoulder 29 of the adjusting rod, ready for another operation.

It will be seen that the entire coin catching device is removable from the base of the case independently from other parts of the 110 machine. The brackets 23 and 24 may be secured upon the top of the case 14. The movement of the forward catcher actuates the swinging frame 7 in the following manner. Said frame is provided with a lever 40 115 secured thereto as at 41, said lever being fulcrumed intermediate its extremities upon the top of the case 14, as shown at 42. The lever 40 is engaged with the rear coin catcher, as shown at 45.

The carriages or feeding plungers 12 are each provided with an arm 43 slotted at its rear extremity as shown at 44. The shaft 10 is provided with a series of pins 46 adjacent to the slotted extremity of each of the arms 125 44, the pins equaling in number the number of magazines with which the machine is provided, the pins being so arranged upon the

shaft that only one pin will successively engage the corresponding arm 44 so that the carriages 12 may be moved forward in successive order, only one carriage being actuated at a time, first one and then another, in successive order. One extremity of the shaft is provided with a pinion 47 meshing with a yielding toothed bar or rack 48 jointedly connected at one end thereof with the car 6 10 as at 49. A spring 50 restores the rack to normal position when free to act. The opposite end of the shaft 10 is provided with a wheel 51, provided with multiple recesses upon its periphery, as shown, the swinging frame carrying a spring pawl 52 to engage the toothed wheel and hold the shaft 10 from turning until released from the wheel 51. On the forward movement of the swinging frame, the shaft is non rotatable, but upon 15 the return movement of said frame, the shaft rotates a single step so as to throw the pins 46 into position successively to engage and actuate the corresponding arms 43. Each of said arms is provided with a forwardly projecting rod 53 jointedly connected with the forward end of the corresponding carriage 12, as at 54, each of the carriages being constructed with parallel bars or supports 55, between which the corresponding rod 53 20 may have a swinging movement. On the forward movement of the swinging frame, the wheel 51 is held by the pawl 52, as above observed, so that it cannot turn. Said pawl is provided with a roller 56, which runs 25 upon an inclined plane or track 57, the action of which is to disengage the pawl from the wheel 51, so that the shaft 10 is free to turn, when the rack and pinion at the opposite end of the shaft come into action. The 30 rearward movement of the swinging frame will obviously engage its pinion 47 with the corresponding rack to turn the shaft one step, causing the corresponding pins 46 to successively act upon the corresponding arms 43 to move the corresponding carriage 35 forward.

On the upper side of each of the arms 43 is a spring 58. The pins 46 are of such length that they strike said springs when the 40 shaft revolves, the springs yielding to permit the pins to pass. When the pins have passed the ends of said springs, the springs return to normal position, and the pins impinge against the end of the corresponding 45 springs to form a contact between the shaft and the corresponding carriage to move the carriage forward upon the forward movement of the frame. It will be obvious that when the actuating pins on the shaft are not 50 in position to impinge against the spring upon a given arm of the carriage, the corresponding carriage will remain stationary, only one carriage being actuated at a time. The carriages, located at the base of the

magazines, when retracted, are in position 65 for a lower article of merchandise in the magazine to fall upon the guide frames or tracks 11 in front of the carriages, the corresponding carriages moving forward said article and forcing it off the track, delivering 70 it upon a chute 59, and from the machine, the chute opening to the exterior of the case. The upper portion of the carriage, as it moves forward, supports the column of merchandise thereabove until the carriage 75 returns. The carriages each have four movements, first the forward movement, as above set forth. But before the carriage recedes, provision is made whereby it shall drop vertically by gravity between adjacent portions 80 of the track. The tracks are each formed with lateral upward guide grooves or channels 60, and lower guide grooves or channels 61, said grooves communicating at proper intervals through upright channels 62 63 85 and 83. The carriages are each provided with laterally extended guide pins 64 traveling in said grooves. The guide pins of the carriage, in the forward movement thereof, run in the upper grooves of the track, and 90 when they reach the upright channels 62, 63 and 83, the pins of the carriage are permitted to drop upon the lower grooves of the track, in position for the carriage to recede. The upper and lower grooves of the track 95 are parallel and spaced a distance apart equal to the thickness of the package of merchandise, permitting the column of merchandise to drop a similar distance when the carriage has moved downward into the lower 100 grooves of the track. The swinging frame is retracted by a spring 64. The return of the carriage, it will be seen, does not interfere with the descent of the next lower article of merchandise in the magazines. When the 105 carriages have returned to their rearward position, springs 65 on the under side thereof lift the corresponding carriages into normal position ready for the next forward movement.

The magazines fit into suitable boxes 66 of the frame. The upper extremities of the boxes are preferably held in place by angle clips 67 attached to the inner walls of the case. A finger piece 68 is shown conveniently located upon the exterior of the base to be engaged by one of the fingers of the operator when forcing in the push rod 31. On the outside of the case an opening 69 into the runway is provided with a hardened slotted plate 70.

To adapt the machine for delivering thinner packages of merchandise, my invention contemplates providing the base of the boxes 66 with filler plates 71 located above 115 and spaced from the tracks 11 to support the articles of merchandise. These filler plates are provided with elongated slots 72

through which the supports 55 may pass, the lateral portions of the carriage being movable at the outer edges of the filler plate.

To prevent the possible dropping of a coin with a string attached into the slots of the coin catchers and removing the coin, I provide a blade 73 at the base of the boxes 66 which will cut the cord on the operation of the coin catchers.

- 10 To indicate when the magazines are empty, I provide a toothed wheel 74, the wheel having the same number of teeth as there are packages in the magazines. The shaft 75 of said wheel is provided with a cam tooth or pin 76 to bear, at the proper time, upon a yoke 77 on the lower extremity of a connecting rod 78, said rod supporting a bell crank lever 79 fulcrumed to the case as at 80. The forward end of the lever supports an "empty" sign slide 81 above an opening in the case. When the last packages in the magazines have been discharged, the bell crank lever is actuated to permit the "empty" sign slide to drop in front of said opening. The said slide may be conveniently arranged above the opening 5 in the case, a clip 82 being provided on the inside of the case, adjacent to said opening, into which the said slide may drop.
- 20 The object of having the forward catcher constructed to telescope into the rear catcher is in order to avoid the operation of the machine when no coin is inserted into the run-way. In such an event the force applied to the push rod would simply cause the front catcher to telescope into the rear catcher without actuating the rear catcher and connected mechanism.

25 To sever a cord which might possibly be attached to, with a view to removing the coin, I prefer to employ a knife indicated at 73 carried by the push rod, the edge of the knife entering an orifice 84 in the base of the run-way to sever the cord. A magnet 35 may be employed, if desired, suitably located to prevent any slugs from descending to the base of the coin run-way. The track 57 upon which the roller 56 of the pawl 52 rides, may be made adjustable, as by means 45 of a cam 86 located therebeneath.

50 The operation of the mechanism will now be understood. A coin inserted in the run-way drops into the slots 16, 17 of the coin catchers. The operator then pushes in the rod 31, moving the coin catchers rearward. Upon releasing the push rod 31, the spring 20 engaging the rack 18 of the rear catcher holds the rear catcher from moving forward until the dog 19 upon the front catcher 60 comes into contact with the dog 22 upon the spring 20, thereby releasing the spring from said rack. When the rear catcher is temporarily held from advancing, the front catcher is restored to normal position by the

spring in the push rod. The two catchers 65 are thus separated, permitting the coin to be discharged from the catchers. The rear movement of the rear catcher, through the instrumentality of the lever 40, actuates the swinging frame to move it forward. The 70 retraction of the swinging frame, by means of the spring 64, restores the rear catcher to normal position when free to move. At the base of each of the magazines the respective tracks receive the lower package of merchandise which is permitted to drop upon the corresponding track by the downward movement of the carriage, the carriage thus descending out of the way of the lower article of merchandise. In its lower position, 75 the carriage is retracted by the corresponding movement of the frame, and when it has reached its limit of rearward movement, it is restored or moved upward into normal position by the action of the spring therebeneath. As each of the carriages moves forward, it not only discharges the lower package of merchandise from the corresponding track, but also rides under the column of packages above the lower package to support said column while the lower package is 80 being discharged.

85 Where packages of merchandise are of a width equal to the space between the corresponding track and the base of the magazine, the filler plate will not be required, but should articles of merchandise be placed in the magazines of less thickness than the space between the lower end of the magazine and the track therebeneath, the filler plate 90 may be employed, the filler plate may be adjusted in position as circumstances may require.

95 What I claim as my invention is:

1. In a vending machine provided with a 100 magazine to contain articles of merchandise, a track located below said magazine, a carriage movable upon said track, a swinging frame to actuate said carriage, and means to actuate said frame, said carriage having a forward, a downward, a rearward, and an upward movement.

105 2. In a vending machine, a magazine for containing articles of merchandise, a track located at the base of the magazine to receive the lower article of merchandise in said magazine, and a carriage having a forward, downward, rearward and upward movement to force said article of merchandise off from said track and to support the 110 remaining articles of merchandise, and means to actuate said carriage.

115 3. In a vending machine, a track having upper and lower guide channels, vertical channels communicating with the upper and lower guide channels, a carriage having a forward movement in the upper channel, a 120 downward movement in the vertical chan-

- nels, a rearward movement in the lower channel, and means to elevate the carriage to normal position.
4. In a vending machine, a swinging frame, a shaft carried by said frame having a step by step rotation, and a carriage actuated by said shaft.
5. In a vending machine, a swinging frame, a shaft carried by said frame having a step by step rotation, and a carriage actuated by said shaft, said carriage provided with a swinging arm engaged by said shaft upon the forward movement of the frame.
6. In a vending machine, a swinging frame, a shaft carried by said frame, having a step by step rotation, said shaft provided with a series of pins, a carriage actuated by said pins one after another to advance the carriage upon the forward movement of the frame.
7. In a vending machine, a swinging frame, a shaft carried by said frame, a carriage actuated by said shaft, and means to give to said shaft a step by step rotation.
8. In a vending machine, a swinging frame, a shaft having a step by step rotation carried by said frame, mechanism to temporarily hold said shaft from turning, and means to release said mechanism.
9. In a vending machine, a swinging frame a shaft carried by said frame, a carriage actuated by said shaft, and means to give a step by step rotation to said shaft.
10. In a vending machine a swinging frame, a shaft carried by said frame, a carriage actuated by said shaft, and means to give a step by step rotation to said shaft, said shaft provided with a wheel recessed upon its periphery, a pawl to engage said wheel to temporarily hold the wheel from turning, and means to release said pawl.
11. In a vending machine, a swinging frame, a shaft having a step by step rotation carried by said frame, a carriage actuated by said shaft, said carriage provided with a swinging arm actuated by the rotation of the shaft to move the carriage forward.
12. In a vending machine, a magazine to contain articles of merchandise, a track below said magazine, mechanism to force forward an article of merchandise upon said track, and a filler plate to support the articles of merchandise above the track.
13. In a vending machine, a case constructed to receive a series of magazines or packages of merchandise, a track at the base of each of said magazines, a reciprocatory carriage to discharge the lower article of merchandise from each of said tracks and to support a column of articles or packages thereabove as the lower article is discharged, and means to actuate said carriages one after another in successive order, said carriages each having a downward movement on the corresponding track when the lower package of merchandise has been discharged to permit the next lower package to drop upon the track.
14. In a vending machine, a case constructed to receive a series of magazines or packages of merchandise, a series of tracks located below said packages upon which the lower package of merchandise is supported, a reciprocatory carriage to discharge said lower package from each of said tracks in successive order one after another, each of the carriages having a downward movement below the upper portion of the corresponding track to permit the next lower article of merchandise to drop upon the track in front of the corresponding carriage.
15. In a vending machine a swinging frame, a shaft provided with a pinion at one extremity thereof, a yielding rack with which said pinion meshes, the opposite end of the shaft provided with a wheel recessed on its periphery, a pawl to engage the recesses of the wheel to hold the shaft temporarily from turning, and means to release said pawl.
16. In a vending machine, a track, a carriage having a forward, downward, rearward and upward movement upon said track, and a spring to cause the upward movement of the carriage.
17. In a vending machine, a track, a swinging frame, a carriage, means to cause a forward and rearward movement of said carriage, said carriage having a downward gravity movement at the limit of its forward stroke, and an upward movement at the limit of its rearward stroke.
18. In a vending machine a swinging frame, a track, a carriage reciprocatory upon said track, a rotatable shaft carried by said frame provided with a series of pins, said carriage having a slotted swinging arm to permit the operation of the pins of the shaft, and a spring upon said arm engageable by the pins of the shaft.
19. In a vending machine, a series of tracks, a reciprocatory carriage upon each of said tracks, a swinging frame, a shaft carried by said frame having a step by step rotation, said shaft provided with a series of pins arranged to move forward the carriages one after another in successive order.
20. In a vending machine provided with a magazine, a track located below said magazine, a filler plate to divide the space between the base of the magazine and the track to support the articles of merchandise in the magazine, and means to force the lower article of merchandise off from the filler plate.
21. In a vending machine, a reciprocatory carriage to discharge the lower package of merchandise from said machine, said carriage movable forward in one plane and returnable in another plane.

22. In a vending machine, means to receive a column of packages of merchandise, a track therebelow upon which the lower package of merchandise may drop, a reciprocating carriage to discharge the lower package of merchandise from the track and to support the remaining packages while the carriage is moving forward, said carriage

movable forward upon one plane and returnable upon another plane. 10

In testimony whereof I have signed this specification in presence of two witnesses.

HOWARD A. LADUE.
